UNITED STATES PATENT OFFICE.

JOHN J. MORGAN, OF NEEDHAM, AND ALFRED DAWES, OF CHELSEA, MASSACHUSETTS; SAID DAWES ASSIGNOR TO SAID MORGAN.

REED FOR MUSICAL INSTRUMENTS.

SPECIFICATION forming part of Letters Patent No. 417,069, dated December 10, 1889.

Application filed August 4, 1888. Serial No. 281,987. (No model.)

To all whom it may concern:

Be it known that we, JOHN J. MORGAN and ALFRED DAWES, respectively of Needham, in the county of Norfolk, and of Chelsea, in the county of Suffolk, both in the State of Massachusetts, have invented certain new and useful Improvements in Reeds for Musical Instruments, of which the following is a specification.

10 This invention relates to reeds for musical instruments in which the ~~reed~~ plate and tongue are made in one piece instead of in separate pieces riveted together.

The invention has for its object to improve 15 reeds of this class with respect to strength, durability, and tone; and it consists in the improvements which we will now proceed to describe and claim.

In the accompanying drawings, forming a 20 part of this specification, Figure 1 represents a top view of a blank suitable for our improved reed. Fig. 2 represents an edge view of the same. Figs. 3 and 4 represent, respectively, a top and an edge view showing the tongue 25 struck up from the blank. Figs. 5 and 6 represent, respectively, a section on line $x-x$ and on line $y-y$ of Fig. 3. Fig. 7 represents a top view of the blank, showing the sides and free end of the tongue trimmed off. Fig. 8 represents a section on line $z-z$ of Fig. 7. Fig. 9 represents a top view of the completed reed, showing the outer surface of the tongue milled off. Fig. 10 represents a section on line $x'-x'$ of Fig. 9.

35 The same letters of reference indicate the same parts in all the figures.

In carrying out our invention we make a flat blank, as shown in Figs. 1 and 2, from tongue metal—that is to say, a composition 40 which has the hardness required for the tongue of a reed—and, placing this blank between a suitable die and force, we pierce out therefrom a tongue a , in doing which we sever the tongue from the plate along the edges and 45 outer end of the tongue and force its inner surface out until it is substantially flush and parallel with the outer surface of the plate, the inner side of the tongue being a part of the smooth inner side of the blank, and therefore perfectly flat and true. This is a feature 50 of great importance, because any unevenness

of the under surface of the reed will affect the tone, the perfection of which depends largely on the evenness of its inner side. In thus piercing out the tongue the base or root 55 b , which connects the tongue to the plate, is compressed between the surfaces of the force and die, so that said root or base, originally of hard or tongue metal, as already stated, is additionally hardened and made so firm 60 and unyielding that it is not liable to be lifted or bent out of place by the manipulations to which the tongue is subjected during the tuning operation.

The next operation is to plane off the edges 65 and free the end of the tongue, as shown in Figs. 7 and 8, thus making the tongue free to vibrate in the slot formed by the piercing out of the tongue. By thus planing the edges of the tongue we remove the roughness of said 70 edges incidental to the operation of piercing out the tongue and make said edges perfectly smooth. The tongue is then milled off in the usual manner, except that said milling is done upon the upper surface instead of upon the 75 lower, as heretofore.

In the manufacture of the smaller sizes of reeds the top surface of the tongue is milled off from its point back to its root, as shown in Figs. 9 and 10. In the smaller sizes of 80 reeds the plate is made so thin that no reduction of the thickness of the walls of the said slot is necessary. In fact, we find that in the smaller reeds the tongues speak or respond to the action of the air more quickly when the 85 plate is not milled off on its under surface. It will be observed that the under side of the tongue retains the smooth rolled surface of the plate or blank from which the reed was made. The smoothness of this surface greatly 90 improves the quality of the tone of the reed as compared with that of a reed whose tongue is reduced or thinned by milling away its under surface. We find that by planing or trimming away the edges of the tongue, so as to 95 make said edges perfectly smooth, the quality of the tone is still further improved.

The thickness of the blank of tongue metal which we employ varies with the size of the reeds, the larger sizes being made of thicker 100 plates than the smaller. By using plates or blanks of hard or tongue metal, as described,

we are enabled to bring the tongues closer to the valves that admit air to the reeds than heretofore, and the plate, being of hard or tongue metal, does not require a marginal lip or flange and can be made of the minimum thickness.

We are aware that reeds have been before made with the tongue and plate in one piece, as shown in Patent No. 2,139 to A. H. Hammond; but in the reed shown in that patent the tongue is reduced by milling off its inner side, which is necessarily left irregular and uneven by the milling-tool, and the root or base of the tongue has not the hard and unyielding quality possessed by the root of our reed-tongue.

We are also aware of the patent to Bray and McClintock, No. 280,789, showing a reed plate and tongue made from one piece of thin sheet metal. In the reed shown in the last named patent soft brass must be used, because tongue metal or hard composition such as we employ cannot be struck up into the form shown, so that to make the reed operative its tongue must be bent out at right angles, or nearly so, to the plate and hardened by hammering. This bending crystallizes and weakens the root of the tongue, which has not the hardness of ours, so that it is more difficult to keep the tongue in place than in our reed.

It will be seen that by making the entire plate and reed of hard or tongue metal and forming the tongue as described, leaving its inner surface level and compacting and additionally hardening the root of the tongue, we produce a reed which is much stronger, of better tone, and more durable and reliable than any heretofore produced.

We claim—

1. A reed composed of a plate and a tongue integral therewith, both composed of a hard or tongue metal, the tongue being pierced out from the plate and having only its outer surface milled, its inner or under surface retaining the original surface of the plate, as set forth. 40

2. A reed composed of a plate and tongue integral therewith, both composed of hard or tongue metal, the tongue being pierced out from the plate and having its outer surface milled and its edges planed, the inner surface 50 of the tongue retaining the original surface of the plate, as set forth.

3. A reed composed of a plate and a tongue integral therewith, both composed of tongue metal, and a compressed or hardened root or 55 base uniting the plate to the tongue, as set forth.

4. A reed composed of a plate and a tongue integral therewith, both composed of hard or tongue metal, the tongue having a level inner 60 surface flush with the outer surface of the plate and an outer surface reduced by milling from the point of the tongue, or thereabout, to the root or base, said root or base having the full thickness of the plate and being additionally hardened by compression, as set forth. 65

In testimony whereof we have signed our names to this specification, in the presence of two subscribing witnesses, this 31st day of July, A. D. 1888.

JOHN J. MORGAN.
ALFRED DAWES.
